UNITED STATES PATENT OFFICE.

THOMAS C. HUTCHINSON, OF DECORAH, IOWA.

TUBE-HOLDER.

1,091,063.

Specification of Letters Patent. Patented Mar. 24, 1914.

Application filed April 29, 1910. Serial No. 558,502.

To all whom it may concern:

Be it known that I, THOMAS C. HUTCHINSON, a citizen of the United States, residing at Decorah, in the county of Winneshiek and State of Iowa, have invented certain new and useful Improvements in Tube-Holders, of which the following is a description.

My invention relates to means for supporting and manipulating a collapsible container whereby the container is permanently supported in a convenient position and the contents of the container is discharged as desired.

The object of my invention is to provide a simple, convenient, clean and durable device of the kind described.

To this end my invention consists in the novel construction, arrangement and combination of parts herein shown and described, and more particularly pointed out in the claims.

In the accompanying drawings wherein like or similar reference characters indicate like or corresponding parts: Figure 1 is a plan view of my device. Fig. 2 is a side elevation of the same. Fig. 3 is an enlarged section taken substantially on line 3—3 of Fig. 1. Fig. 4, is a section taken substantially on line 4—4 of Fig. 3. Fig. 5 is a section taken substantially on line 5—5 of Fig. 2. Fig. 6 is a detail of the blank for forming the frame of my device. Fig. 7 is a detail of a part of the key for collapsing the container. Fig. 8, is a side elevation of a simple form of my device. Fig. 9, is a plan view of the form of my device shown in Fig. 8.

In the drawings the frame of my device consists in the preferred construction shown, of a suitably formed sheet of material 1 with its side margins 2—2 bent at substantially right angles to the body portion, and the end 3 bent at substantially right angles in the opposite direction. The extremities 4—4 of the parts 2—2 are bent inward to lie in substantially the same plane as the part 3. The parts 4—4 and 3 are formed to jointly operate as a foot or base for my device and are provided with suitable openings 5—5 and 6 respectively for attaching my device in position by means of suitable screws, nails or other fasteners, the several parts forming a rectangular trough closed at the foot end. The opposite end of the sheet 1 is provided with a

part 7 adapted to be bent inward to serve as a partial closure for the outer end of the trough and the sides 2—2 are each provided with a projecting part 8, also bent inward and positioned in substantially the same plane and arranged to coöperate with the part 7 to close the end of the trough or box. The parts 8—8 and 7 are each preferably so formed that when in operative position a slight space is left open between them with a circular or otherwise suitably formed aperture 9 formed jointly in their proximate edges, adapted to receive a portion of a collapsible container 10 preferably its outlet nozzle 11 and resiliently engage the same and prevent its longitudinal movement. The outlet end or nozzle 11 preferably projects at the end of the frame, so that a cap 12 or other suitable closure may be applied to the outlet to prevent evaporation and loss of the contents of the container. The several parts are preferably so formed that when the cap 12 is screwed down upon the nozzle 11 the cap will engage the parts 7 and 8—8 and positively lock the container in position upon the holder. Suitable means are also preferably provided to support the opposite end of the container and gradually collapse the same to expel its contents when desired. In the form shown, the sides 2—2 are each provided with a longitudinal slot 14. A cylindrical key 15 of suitable length to extend across the space between the sides 2—2 and also through the slots 14 is provided. A longitudinal slot 16 arranged to receive the end of the container is formed in the key 15 and a head or handle 17 is provided at one extremity of the key so that after a portion of the container is inserted in the slot the key may be manually rotated to wind the container upon the periphery of the key to collapse the container and thereby expel the material contained therein through the outlet nozzle. In the form shown, a roller 18 is also positioned in the space between the sides 2—2 with its shaft at each end projecting through the slots 14 and a suitable spring 19 is arranged near the outer side of each of the sides 2 with one end of the spring engaging the key 15 and the opposite end engaging the shaft of the roller 18 and resiliently forcing the roller against the periphery of the key, so that when a container is wound upon the key the roller 18 will press against the same and prevent any of the material with which

the container is filled remaining in the collapsed portion. In practice it has been found that the container is wound more evenly and smoothly upon the key if resilient means is provided to engage the key and hold the container extended. Where this is desired a yoke 20 is provided, formed to engage the key 15, near its extremities and suitable means are provided to engage the yoke 20 and resiliently draw it toward the foot or base of the frame. Any suitable means may be provided for this purpose, in the form shown a shaft 21 is rigidly mounted upon the frame 1 by means of a hood or yoke 22 and a pedestal or foot 23. A drum 24 is rotatably mounted upon the shaft 21 with a spring 25 or other suitable means resiliently connecting the drum to the shaft. A cord or flexible connection 26 is wound upon the periphery of the drum with one end extending through a suitable opening 27 in the hood 22 and with the free end of the cord attached to the yoke 20, the several parts being so proportioned and arranged as to resiliently draw the yoke toward the drum with the desired force. When thus arranged a ratchet wheel 28 is preferably provided upon the key 15 and a spring actuated dog or pawl 29 is provided upon the yoke 20 arranged to engage the ratchet wheel 28 to prevent the tension of the resilient parts unwinding the key 15 and thereby releasing it from the container 10.

In Figs. 8 and 9 a simpler form of my device is shown in which a strip of suitable material 30 is bent to form a U shaped frame with the extremities 31-31 bent outward to serve as a base, the part 32 connecting the straight sides of the frame is provided with a threaded opening 33 adapted to engage a threaded outlet nozzle 34 upon the container 35. Slots 36 are provided in the side walls of the frame substantially as before described and a key 37 provided with a slot 38 is arranged to extend across the space between the side walls and through the slots to receive a portion of the container upon its periphery as before described. A part at one end of the key is bent as at 39 to operate as a handle for manually rotating the key to collapse the container by winding the same upon the periphery of the key.

Having thus described my improvement it is obvious that various immaterial modifications may be made in my device without departing from the spirit of my invention hence I do not wish to be understood as limiting myself to the exact form or construction shown.

What I claim as new and desire to secure by Letters Patent is:

1. A device of the kind described, comprising a frame and means rigidly mounted upon said frame adapted to engage a col-

lapsible container near its outlet, in combination with a pair of rotatable members mounted upon the frame adapted to engage the opposite end of the container between them to support the same and to gradually collapse said container and resilient means tending normally to maintain said container extended. 70

2. A device of the kind described, comprising a frame and means rigidly mounted upon said frame adapted to engage a collapsible container near its outlet, in combination with a pair of rotatable members mounted upon the frame and adjustable longitudinally thereof adapted to engage the opposite end of the container between them to support the same, and means for manually operating said rotatable members to gradually collapse said container. 80

3. A device of the kind described, comprising a frame and means rigidly mounted upon said frame adapted to engage a collapsible container near its outlet and maintain said outlet in a conveniently accessible position, in combination with a pair of rotatable members, slidably mounted upon the frame adapted to engage the opposite end of the container between them to support the same and to gradually collapse said container, and means for rigidly securing said frame in position. 90

4. A device of the kind described, comprising a frame and means rigidly mounted upon said frame adapted to engage a collapsible container near its outlet and maintain said outlet in a conveniently accessible position, in combination with a pair of rotatable members slidably mounted upon the frame adapted to engage the opposite end of the container to support the same and to gradually collapse the container, and means for locking said members against rotation in one direction. 100

5. A device of the kind described, comprising a frame and means rigidly mounted upon said frame adapted to engage a collapsible container near its outlet, in combination with rotatable mechanism adapted to engage the opposite end of the container to support the same and to gradually collapse said container, and resilient means tending to normally maintain said container extended. 110

6. A device of the kind described, comprising a frame and a plurality of resilient members rigidly mounted upon said frame adapted to jointly engage a collapsible container near its outlet and maintain said outlet in a conveniently accessible position, in combination with rotatable mechanism upon said frame adapted to engage the opposite end of the container to support the same, and means for manually operating said engaging mechanism to gradually collapse said container. 120

7. A device of the kind described, comprising a frame and a plurality of members rigidly mounted upon said frame adapted to jointly engage a collapsible container near its outlet and maintain said outlet in a conveniently accessible position, in combination with rotatable mechanism slidably mounted upon the frame adapted to engage the opposite end of the container to support the same and to gradually collapse said container, and means for locking said mechanism against rotation in one direction.

8. A device of the kind described, comprising a frame and resilient means upon the frame adapted to engage a collapsible container near its outlet and maintain said outlet in a conveniently accessible position, in combination with mechanism mounted upon said frame adapted to engage the opposite end of the container to support the same and means for manually operating said engaging mechanism to gradually collapse said container.

9. A device of the kind described, comprising a frame and a plurality of resilient members upon said frame adapted jointly to engage a collapsible container near its outlet and maintain said outlet in a conveniently accessible position, in combination with mechanism slidably mounted upon the frame adapted to engage the opposite end of the container to support and gradually collapse the same.

10. A device of the kind described, comprising a frame and means rigidly mounted upon said frame adapted to engage a collapsible container near its outlet, in combination with rotatable mechanism slidably mounted upon said frame adapted to engage the opposite end of the container to support the same, means for manually operating said engaging mechanism to gradually collapse said container, and resilient means tending to normally maintain said container extended.

11. A device of the kind described, comprising a frame and resilient means upon said frame adapted to engage a collapsible container near its outlet and maintain said outlet in a conveniently accessible position, in combination with rotatable mechanism adjustably mounted upon the frame adapted to engage the opposite end of said container to support and gradually collapse the container.

12. A device of the kind described, comprising a frame, and means rigidly mounted upon said frame adapted to engage a collapsible container near its outlet, in combination with mechanism adapted to engage the opposite end of the container to support the same and to gradually collapse said container and resilient means tending to normally maintain said container extended.

13. A device of the kind described, comprising a frame adapted to support a collapsible container and having a part arranged to engage the nozzle of said container with the end of said nozzle projecting beyond said frame in position to receive a part adapted to close said nozzle and lock said container to said frame, in combination with rotatable mechanism upon said frame adapted to engage the opposite end of the container to support the same, and means for manually operating said engaging mechanism to gradually collapse said container.

14. A device of the kind described, comprising a sheet metal frame adapted to support a collapsible container and having a part arranged to engage the nozzle of said container with the end of said nozzle projecting beyond said frame in position to receive a part adapted to close said nozzle and lock said container to said frame, in combination with rotatable mechanism upon said frame adapted to engage the opposite end of the container to support the same, and means for manually operating said engaging mechanism to gradually collapse said container.

15. A device of the kind described, comprising a frame formed of a single piece of sheet metal adapted to support a collapsible container and having a part arranged to engage the nozzle of said container with the end of said nozzle projecting beyond said frame in position to receive a part adapted to close said nozzle and lock said container to the frame, in combination with rotatable mechanism upon said frame adapted to engage the opposite end of said container to support the same, and means for manually operating said engaging mechanism to gradually collapse said container.

16. A device of the kind described, comprising a frame adapted to support a collapsible container and having a part arranged to engage the nozzle of said container with the end of said nozzle projecting beyond said frame in position to receive a part adapted to close said nozzle and lock said container to said frame, and means formed integrally with said frame for rigidly securing the frame in position, in combination with rotatable mechanism upon said frame adapted to engage the opposite end of the container to support the same and means for manually operating said engaging mechanism to gradually collapse said container.

17. A device of the kind described, comprising a frame adapted to support a collapsible container and having an opening formed through a part arranged to receive the nozzle of said container with the end of said nozzle projecting beyond said frame in position to receive a part adapted to close

said nozzle and lock said container to said frame, in combination with rotatable mechanism upon said frame adapted to engage the opposite end of the container to support the same, and means for manually operating said engaging mechanism to gradually collapse said container.

In testimony whereof, I have hereunto signed my name in the presence of two subscribing witnesses.
